FIGURE 1 is a perspective view of my new design for a light fixture, with the observer's eye level being approximately at the point of intersection of the wires;

My design resides in the portions of the light fixture shown in full lines.

I claim:

The ornamental design for a light fixture, as shown and described.
